CLOCK OR SIMILAR ARTICLE

Mark Wallach, 220 E. 63rd St.,
New York, N.Y. 10021

Filed Mar. 2, 1970, Ser. No. 21,686

Term of patent 14 years

Int. Cl. D10—01

U.S. Cl. D42—7

FIG. 1 is a front-elevational view of a clock or similar article showing my new design;

FIG. 2 is a side elevational view thereof;

FIG. 3 is a rear elevational view thereof;

FIG. 4 is a top view thereof;

FIG. 5 is a bottom view thereof.

I claim:

The ornamental design for a clock or similar article, as shown.
